[57] ABSTRACT

A timepiece comprises a click device disposed between a first hour wheel and a second wheel carrying an hour hand. The first wheel is freely mounted on a shoulder of the second wheel and is held on the shoulder by a leaf spring secured to the second wheel. A boss or recess at the free end of the spring cooperates with one of twelve complementary recesses or bosses on the felloe of the first wheel to hold the first wheel in any one of 12 positions, whereby during use of the timepiece the hour hand can be made to jump by steps by 1 hour.

FIG. 1

FIG. 2

FIG. 4

FIG. 3

FIG. 5

TIMEPIECE CLICK DEVICE

The invention relates to timepieces or components of timepieces comprising a click device between a first hour wheel and a second wheel carrying or being adapted in use of the component to carry an hour indicator such as a hand, this click device permitting the angular position of these two wheels to be changed step-wise.

Numerous devices are known of this type which usually comprise a jumper co-operating with a star-wheel having twelve teeth, or a pawl and a ratchet wheel. These known devices are fairly complicated and of considerable thickness.

The object of the present invention is the provision of a click device assembly which is simple to construct and of reduced thickness.

According to the invention, this click device assembly is such that the first hour wheel is mounted freely on a shoulder of the second wheel, the first wheel being maintained on the shoulder by a leaf spring secured to the second wheel and having at least one arm provided towards a free end thereof with means co-operating with complementary means carried by the first wheel for holding the wheels in any one of a plurality of discrete relative angular positions.

The accompanying drawings show, by way of example, two embodiments of the invention. In the drawings:

FIG. 1 is a plan view of a first embodiment;

FIG. 2 is a cross-section along the line A—A' of FIG. 1;

FIG. 3 is a similar cross-sectional view of a second embodiment;

FIG. 4 is a modified detail from FIG. 2; and

FIG. 5 is a modified detail from FIG. 3.

The embodiment shown in FIGS. 1 and 2 comprises a first hour wheel 1 and a second wheel 2 carrying an hour hand 3 on its stem or pipe 4.

The first hour wheel 1 is freely mounted on a shoulder 5 of the wheel 2 and maintained on this shoulder by a spring 6 provided with four symmetrical radially extending arms 6a. Spring 6 is secured to the wheel 2 by a ring 7 tightly fitted on a projecting sleeve of this wheel and by bosses 8 provided on the wheel 2 which engage in notches 9 in the spring; the ring 7 maintains the spring 6 axially, the bosses 8 and the notches 9 establishing the relative angular position of the spring 6 and the wheel 2.

The arms 6a of the spring 6 each have means co-operating with complementary means carried by the wheel 1 so as to set the relative angular position of wheels 1 and 2. These means include a boss 6b towards the free end of each arm engaging a respective one of 12 recesses or, as shown, openings 10 provided in the felloe of wheel 1. Alternatively, as indicated by FIG. 4 12 bosses 10a could be provided on the wheel 1 entering into recesses or openings 6c provided in the arms 6a. The free ends of arms 6a could alternatively be folded over, for example into V-shape 6d, and lodge in grooves or other recesses 10b of a complementary form provided in the felloe of wheel 1, as indicated by FIG. 5.

The hour wheel 1 is driven by a pinion 11 of the time-piece gear train. A correction wheel 12 operated by a pinion in conjunction with a manually-operable correcting device enables variation of the angular position of the wheel 2 relative to wheel 1 by steps each corre-

sponding to a change of the indication of hand 3 by 1 hour, without affecting the working of the watch.

In the first embodiment shown, the wheel 2 indirectly drives the members of a calendar, by means of a wheel 13 making one rotation in 24 hours.

In FIG. 3, the same members carry the same reference numerals. However, the hour wheel 1 is provided with a stem or pipe 1a carrying a second hour hand 1b. Pipe 1a is connected to the wheel 1 by an integral flange 1c with a rim 1d tightly fitted within wheel 1.

This thus enables different indications to be given by the hour hands, one of which may be a reference hour, GMT for example, the other a local time.

In this embodiment, a calendar could be driven by indirect means comprising a 24 hour wheel 13 meshing with wheel 1. Alternatively it is possible to drive a calendar by a 24 hour wheel 13a; meshing with wheel 2, as also shown in FIG. 3.

The advantages of the described click device assemblies are that they are of a minimal thickness, are simple to construct, and form a unitary assembly which can facilitate the operations of fitting into a watch or other timepiece.

What is claimed is:

1. In a timepiece comprising a click device between a first hour wheel and a second wheel carrying an hour indicator, the improvement wherein the first hour wheel is mounted freely on a shoulder of the second wheel, the first wheel being maintained on the shoulder by a leaf spring secured to the second wheel, and said spring having at least one arm extending to a free end and provided towards said free end with means co-operating with complementary means carried by said first wheel for holding said first and second wheels in any one of a plurality of discrete relative angular positions.
2. A timepiece in accordance with claim 1 wherein the first wheel has a pipe carrying a second hour indicator.
3. A timepiece in accordance with claim 1 wherein the means establishing the relative angular positions of said first and second wheels include a boss on said arm of said spring, and 12 cooperating recesses or openings provided in the felloe of said first wheel.
4. A timepiece in accordance with claim 1 wherein the means establishing the relative angular positions of said first and second wheels include 12 bosses on the felloe of the first wheel and a cooperating recess or opening in said arm of said spring.
5. A timepiece in accordance with claim 1 wherein the means establishing the relative angular positions of said first and second wheels include a folded over end of said arm of the spring, said folded-over and co-operating with complementary grooves provided in the felloe of the first wheel.
6. A timepiece in accordance with claim 1, including a 24 hour wheel means for operating a calendar, and means for operatively connecting said first hour wheel with said 24 hour wheel means.
7. A timepiece in accordance with claim 1, including a 24 hour wheel means for operating a calendar, and means for operatively connecting said second wheel with said 24 hour wheel means.
8. A timepiece in accordance with claim 1 including a motion-work connected with the first wheel to rotate said wheel, and correcting wheel means for rotating the second wheel to enable setting of the first and second wheels in a selected one of said discrete angular positions.
